[57] CLAIM

The ornamental design for a multifaced doll, as shown and described.

DESCRIPTION

FIG. 1 is a front view of a multifaced doll showing my new design;

FIG. 2 is a top view of the doll shown in FIG. 1;

FIG. 3 is the reverse side of the doll shown in FIG. 1; FIG. 4 is a front view of the doll shown in FIG. 1 with the skirt cut away to show the lower segment which is configured as the face and upper body portion of another doll in the inverted position;

FIG. 5 is the doll as shown in FIG. 4 with the skirt pulled down over the upper body portion of the doll that appears in FIGS. 1 through 3;

FIG. 6 is the reverse view as shown in FIG. 3 with the skirt cut away to show the lower segment which is configurated as the face and upper body portion of another doll in the inverted position; and,

FIG. 7 is the doll as shown in FIG. 6 with the shirt pulled down over the upper body portion of the doll that appears in FIGS. 1 through 3 above. FIG. 7 is the reverse of the doll as it appears in FIG. 5.

FIG. 2

FIG. 1
